United States Patent Office

Des. 218,448
Patented Aug. 18, 1970

218,448

DESK

Sidnor Tebbs Chichester, Jr., 2529-A P St. NW,
Washington, D.C. 20007

Filed Mar. 12, 1969, Ser. No. 16,189

Term of patent 14 years

Int. Cl. D6—01

U.S. Cl. D33—7

FIG. 1

FIG. 2

FIG. 3

FIG. 4

FIG. 5

FIG. 6

FIG. 7

FIG. 1 is a perspective view of the desk comprising the invention;

FIG. 2 is a rear elevational view of the desk;

FIG. 3 is a bottom plan view of the desk;

FIG. 4 is a side elevational view of the desk;

FIG. 5 is a side elevational view of an alternative desk design in accordance with the invention; with the front to rear dimension of the pedestals in this form being relatively abbreviated;

FIG. 6 is a bottom plan view of the FIG. 5 alternative desk design, and

FIG. 7 is a rear view of the FIG. 5 alternative desk design.

I claim:

The ornamental design for a desk, substantially as shown and described.
